UNITED STATES PATENT OFFICE

THOMAS SPENCER MILLER, OF SOUTH ORANGE, NEW JERSEY

ENGINE

Application filed July 7, 1922. Serial No. 573,502.

My invention relates to new and useful improvements in tension engine, and particularly contemplates improved means for controlling or regulating the tension of a line wound upon a power-driven drum.

My invention consists of certain novel parts and combinations of parts particularly pointed out in the claims.

The following is a description of certain forms of my invention at present preferred by me, but it will be understood that various modifications and changes may be made therein without departing from the spirit of my invention, and without exceeding the scope of my claims.

My invention will best be understood by reference to the accompanying drawings in which, Figure 1 is a top plan view of one embodiment of my invention; Fig. 2 is a side view of the construction shown in Fig. 1; Fig. 3 is an enlarged view, partly in section, of certain features of construction embodied in Figs. 1 and 2; Fig. 4 is a diagram of connections; Fig. 5 is an end view of a brake device which is preferably used with a high efficiency gearing; Fig. 6 is a plan view, partially in section, of a modification of my invention embodying an automatic arrangement for operating the controller for the motor; Fig. 7 is a side view, partially in section, of Fig. 6, and Fig. 8 is a detail view.

Referring to the drawings by characters of reference, 1 designates a bed frame or base, the same carrying pillars or standards 2 provided at their upper portions with aligning bearings 3 in which is mounted a drum shaft 4. Upon the drum shaft is mounted a drum 5 having end flanges 6, said drum being suitably fixed to said shaft so as to rotate therewith. Upon the shaft 4 is also fixed a gear 7 which meshes with a pinion 8 mounted on a power transmission shaft 9 arranged in suitable bearings 10, 11 and 12 mounted on standard 13 and on a gear housing mounted on a bed plate, said gear housing comprising a lower chamber portion 14 and an upper cover or cap piece 15. On the shaft 9 is a large worm gear 16 (see Fig. 3), which meshes with a worm 17 mounted fixedly on a horizontal shaft 18. The shaft 18 is arranged

to rotate and also to slide lengthwise in suitable bearings carried preferably by the lower portion 14 of the gear housing. Each of these bearings preferably comprises a hollow boss 19 formed integral with the lower part 14 of the gear housing, and in longitudinal alignment with each other. Within each of the bosses 19 is arranged a bearing sleeve 20 surrounding the shaft 18 and provided at its outer end with a securing flange 21 through which passes fastening stud bolts 22 threaded into the boss, whereby the sleeve is held in position. Each bearing sleeve preferably contains suitable packing material 23 held in place by a packing gland 24 secured by adjustable stud bolts 25 passing through a flange on said gland and threaded into the outer end of the sleeve 20. Each sleeve 20 is of less diameter than the bore of the boss 19, so as to provide an annular space 26 surrounding said bearing sleeve to provide a chamber, for a purpose to be presently described. The shaft 18 is provided at one end with a squared or angularly-faced portion 27 which slidably engages a correspondingly formed socket 28 in a bearing coupling or sleeve 29 which turns in a bearing 30 on a standard 31, the bearing being arranged in line with said shaft 18. The bearing coupling 29 is connected to the drive shaft 32 of a reversible electric motor 33, said coupling 29 being so connected to the shaft 32 as to revolve therewith, whereby rotary motion is transmitted from the motor to the shaft 18. The polyfaced end 27 of the shaft 18 arranged in engagement with the correspondingly formed socket in the bearing coupling 29 provides for longitudinal movement of said shaft relative to said bearing coupling without disconnecting the driving connection between said shaft and coupling.

Mounted on one end portion of the shaft 18 is a thrust collar or flange 34, between which and a follower disc 35, also surrounding said shaft, is any suitable form of anti-friction bearing 36. Located in the boss 19 containing the disc 35, and between said disc and the flange or head 21 on the bearing sleeve 20, is arranged a spiral spring 37, this spring being arranged and adapted to resist endwise move-

ment of the shaft 18 toward the left, as viewed in Fig. 3, when the drum is overhauled by tension on a line wound thereon. At the end portion opposite to that just described, the shaft 18 is provided with a thrust collar or flange 38 fixed thereto, and between which and a slidable sleeve 39 in the associated boss 19 is a suitable anti-friction bearing 40. The sleeve 39 surrounds the bearing sleeve 20, heretofore described, and between one end of the said sleeve 39 and the head 21 of the bearing sleeve is a coil spring 41 of less expansive force than the spring 37, heretofore described; the spring 41 being adapted to exert its force against the sleeve 39 to thrust the shaft 18 toward the left as viewed in Fig. 3, to maintain proper contact and prevent backlash between the elements 34, 36, 35, 27 and 21. In the preferred form of my invention the worm gear 16 and engaging worm 17 are of high efficiency wherein a certain torque in the drum will turn the worm. When the line on the drum is placed under tension which would tend to overhaul the drum, and the electric brake applied to the shaft in the manner hereinafter described the worm 17 will not rotate, but will move the shaft 18 toward the left, as viewed in Fig. 3, and place the spring 37 under compression. It will also be seen that the spring 37 being under compression, any reduction in tension on the line will result in said spring exerting its force to thrust the shaft 18 in a direction opposite to that just described. These motions of the shaft 18, as regulated by the spring 37, I employ to control the operation of the motor so as to regulate the tension on a line wound on the drum. For this purpose I provide a suitable control for causing the motor to drive the drum in the winding-in direction when slack greater than that desired occurs in said line, and to drive the motor in the reverse direction to pay out the line when the tension of the line is greater than that desired. The control maintained is as follows:

The outer end of the shaft 18 is arranged to project beyond the packing gland 24, as shown at 42, and is provided with an annular groove 43 in which is arranged a collar 44 to which is pivotally connected as at 45, one end of a yoke or link 46, the opposite end of which is pivotally connected, as at 47, to one end of a rocking lever 48 pivoted intermediate its ends, as at 49, at any suitable point upon the frame. The opposite end of the lever 48 is pivotally connected, as at 50, to one end of a rack bar 51, which slidably projects through a guide block 52 on a hand-lever 53, which lever is suitably fulcrumed, as at 54. Arms or members 55 are secured to the shaft 54, and each arm carries a contact 56, said contacts cooperating with fixed segmental contacts, indicated generally at 57, the fixed contacts preferably being arranged in two groups 57^a and 57^b at the right and at the left, respec-

tively, in Fig. 4, with a free space between the two groups, so that when the lever 53 occupies the position illustrated in Fig. 3, the contacts 56 occupy a neutral position between the two groups of contacts 57^a and 57^b and the electric brake which will be more fully hereinafter described becomes operative. When the handle 53 is moved to the right, as viewed in Fig. 3, the contacts 56 are brought into contact with the contacts 57^a, thereby connecting the armature 33^a and field 33^b of the motor to the line L'. L², by a circuit which will be readily traced in Fig. 4, the current passing through the armature and field of the motor in series and in a direction to produce in the motor a torque tending to pay out the line. The contacts of the controller, which controller I have indicated generally at A, are so arranged that when the controller is moved to the first position in either "forward" or "reverse", all of the resistance of a resistance member 58 is included in the motor circuit, the resistance being gradually cut out as the controller is moved through the successive positions until in the last position of the controller, all of the resistance is cut out, the operation of the controller in this respect being the same as the usual operation of controllers of the type illustrated. When the handle 53 is moved to the left from the neutral position, the contacts 56 are brought into engagement with the contacts 57^b and the motor is energized, but the current through the field of the motor is now in a direction the reverse of what it was with the handle at the right, and a torque is produced in the motor tending to wind in the line on the drum. While I have illustrated a plain series motor, it will, of course, be understood that my invention is not limited to a motor of this particular type, as any reversible electric motor may be used. Upon the hand-lever 53 is a manually operated latch 61^a adapted to cooperate with the rack teeth 51^a on the rack bar 51, so that the lever may be adjustably connected to said rack bar lengthwise of the latter.

When used for mooring, the line wound on the drum is connected to the desired object, the latch 61^a on the hand-lever is released from the rack bar 51 and said hand-lever is moved to the left thereby closing a circuit to the motor to drive the drum in the winding direction until the desired tension is obtained on the line. When the desired tension is obtained, the control spring 37 will be placed under compression, due to the movement of the shaft 18 lengthwise under the pull of the line, and the rack bar 51 will be adjusted relative to the lever 53 a distance corresponding to the movement of the shaft 18. The lever 53 is then operated to bring the contact arm 55 to neutral, and the latch 61 is reengaged with the said rack bar 51 whereby the latter is locked to the hand-lever. When the

contact arm is brought to neutral the current will be thrown off the motor and the latter brought to rest, and the expansive force of the spring 37 and the pull on the line are balanced, the contact arm 55 being held at neutral so long as this balanced condition of spring power and line pull exists.

Should, for any reason, the line tension be increased above that determined by the neutral adjustment or set-up just described, the drum will be overhauled slightly but relative rotary movement between the worm wheel 16 and worm 17 is prevented by the brake. The shaft 18 is thereby moved toward the left, as viewed in Fig. 3; this movement of the shaft 18 swings the lever 53 to the right thereby bringing the contacts 56 into engagement with the contacts 57^a, which closes the motor circuit to drive the latter in the reverse direction to pay out the line until the increase of tension on the line is relieved or reduced, and the original tension is reestablished. When the desired line tension is again produced, by the operation just described, the force exerted on the spring 37 from the overload is relieved and the spring resumes its original set position, pushing the worm shaft 18 so as to swing the lever 53 to bring the controller arm 55 back to neutral, whereupon the line is held until a further change of tension therein takes place.

If the line should slacken and the tension therein consequently be reduced, the force or resistance originally exerted on the spring 37 by the line is reduced, and said spring pushes the worm shaft 18 in the opposite direction from that above described, which causes the lever 53 to be swung to move the contacts 56 from neutral to engage the forward contacts 57^b to cause the motor to be driven forward, thereby rotating the drum to take up the slack so that the tension in the line will be increased to the desired point. When the tension in the line is restored, the worm shaft 45 is thrust lengthwise toward the spring 37 to compress the same to the original degree, and in so doing the lever 53 will be automatically moved to shift the contact arm back to neutral, whereby the line is held at the desired tension initially determined. By the construction described, it will be seen that so long as the predetermined tension is present in the line, no current will be consumed by the motor as the brake holds the drum or the motor. The invention will be found particularly applicable to ship mooring, where rise and fall of the tide causes the tension in the mooring line to vary considerably and make adjustment of the tension desirable, my invention serving to automatically regulate the tension, the presence of slack to an undesirable degree causing the line to be automatically wound in, and the presence of overstresses resulting in the line being automatically paid out until

the overstress is relieved and the desired tension is established.

In Fig. 5 I have illustrated one form of brake, comprising two braking arms 60 and 61 located on opposite sides of the shaft 32 and pivoted, respectively, at 63 and 64 to the frame. An elbow lever 65 is preferably pivoted on one of the brake arms, as at 62, on the arm 61, a short arm of the elbow lever 65 extending downwardly, as indicated in dotted lines, and connected to the upper end of the brake arm 60 by a link 66. The end of the long arm of the elbow lever 65 is connected by a stem 67 to a core 68 within a solenoid 69. The weight of the core normally operates to pull the end of the elbow lever 65 downwardly and thus pull together the upper ends of the braking arms 60 and 61, so that the brake is normally applied when the solenoid 69 is deenergized. When the solenoid is energized, the core 68 and the end of the elbow lever 65 are raised, the braking arms separated, and the brake released. The diagram of connections for controlling the motor when the brake is utilized is illustrated in Fig. 4, from which it will be apparent that the brake coil is connected across the line conductors L', L² through the controller so that it is normally deenergized when the controller is in the neutral position, and when the controller is moved to either side of neutral position the brake coil is energized at the first notch of the controller and remains energized while the motor is energized.

With the arrangement illustrated in Figs. 1, 2 and 3, variations in tension of the line may result in an increase or decrease of the length of the line. Over an extended period, where the invention is used for towing, increases and decreases in tension of the line under certain conditions about compensate for each other, but where the invention is used for mooring, the rise or fall of the tide, and other factors met with in mooring, may cause a permanent increase or decrease in the length of the line. In the former case, when used for towing, a permanent increase or decrease, however, may not occur until after an extended period and can readily be corrected by suitably operating the controller.

Under some conditions, and particularly when my invention is used for towing, the arrangement illustrated in Figs. 1, 2 and 3 might result in an undesirable permanent increase or decrease in the towing length of the line. For example, when the engine is once adjusted, an increase in speed in the towing vessel would result in a permanent increase in tension on the towing line, and this condition, with the arrangement of Figs. 1, 2 and 3, would result in paying out too much line.

In Figs 6 and 7, I have illustrated an

automatic arrangement for overcoming the foregoing difficulties and which tends to produce a permanent length of line. In the arrangement here shown, the motor 33 drives 5 a worm and worm wheel through the shaft 32 in the same manner as described in connection with Figs. 1, 2 and 3. The end of the shaft 18 in Fig. 7 corresponds to the left-hand end of the shaft similarly indicated in Fig. 3. The end of the shaft 18 is connected by a yoke 70 to the lower end of an arm 71 secured on a shaft 72. An arm 73, also secured on the shaft 72, is connected at its upper end by a link or links 10 74 to one end of a stem or rod 75 slidably mounted in a bearing member 76 and threaded at its opposite end, as at 77. The threaded end 77 of the rod 75 is received in the end of a shaft 78 slidably received in a sleeve 79 but feathered thereto so that the two rotate together. The sleeve 79 has its bearing at 80 in a part of the frame, and is preferably provided at its outer end with a hand-wheel 81, and near the other end with a bevel-gear 25 82 forming a part of the automatic arrangement. The inner end of the shaft 78 is provided with an annular groove 83 in which is received a collar 84 engaged by a yoke member 85 secured to or forming a part 30 of an arm 86 secured on the shaft 54, the rotation of the latter operating the controller A in the same manner as described in connection with Figs. 1, 2 and 3. By manipulation of the hand-wheel 81, the controller 35 55 may be operated in the same manner as that described in connection with Figs. 1, 2 and 3. Assuming that the controller and the associated parts have been adjusted, then by rotating the hand-wheel 81 to the right or to the left, the shaft 78 is correspondingly rotated and is moved to the right or to the left on the threaded stem 75, thereby moving the upper end of the arm 86 to the right or to the left and correspondingly operating the controller. 40 45

I will now describe the automatic arrangement for operating the controller: A shaft 87 has its bearing at 88 in a bracket 89 secured to the frame of the engine. One end 50 of the shaft 87 is provided with a bevel-gear 90 loose on the shaft 87 meshing with the bevel-gear 82 on the sleeve 79. On the opposite end of the shaft 87 is mounted a gear 91 loose on the shaft 87 and meshing with the gear wheel 7. The shaft 87 is rotated 55 from the gear 91, preferably through a friction clutch comprising a friction member 92 slidably longitudinally of the shaft 87 but rotating therewith. The member 92 is provided with a hub 93 and with a flange 94 frictionally engaging the side of the gear wheel 91. A coil spring 95 is interposed 60 between the end of the hub 93 of the friction member and a collar 96 on the shaft 87 which is held in position by lock nuts 97. A clutch

member 98 is secured to rotate with the shaft 87 but is movable longitudinally thereon, the same being operated by any suitable mechanism. The clutch member 98 is formed with clutch jaws engaging a cooperating clutch part formed on the gear 90, as shown in Fig. 6, so that when the clutch member 98 is moved into engagement with the corresponding clutch member formed on the gear 90, the gear 90 is rotated by the shaft 87 and correspondingly rotates the gear 82, thereby imparting movement to the controller in the same manner as described in connection with the usual control. 70 75

It will be understood that the device illustrated in Figs. 6 and 7, by disconnecting the clutch member 98 and thereby disconnecting the automatic control, may be operated manually, the same as the device illustrated and described in Figs. 1, 2 and 3. By closing the clutch of the automatic arrangement, the device operates automatically in the following manner: Assume that the line on the towing engine or winch, which is preferably located on the towing vessel, is subjected to an increase in tension by a more or less permanent increase of speed of the towing vessel. The increase in tension on the line will move the end of the shaft 18, as viewed in Fig. 7, to the right, thereby moving the stem 75 and the upper end of the arm 86 to the left to operate the controller to reverse position, thereby rotating the motor in a direction to pay out the line. As soon as the motor begins to rotate, however, the gear 7 rotates the gear 91, and through the described connections operates the controller back toward the neutral position, so that when pay out has been sufficient to bring controller to neutral, the spring 37 will be compressed more and the normal tension higher than was previously the case, thus preventing further normal pay out of line and causing the winding in of line lost by previous increase. The line will thus be maintained at constant, or substantially constant, length. 100 105 110

When normal tension is on the line, therefore, the controller is in the neutral position, the motor is deenergized, and the drum is prevented from rotating. A temporary variation of the tension in the line moves the controller to close a circuit to the motor, thereby causing the same to rotate in a direction to correct the variation in tension. As soon as the motor, however, begins to rotate, then the automatic device is operated in response to the rotation of the motor which moves the controller in a direction to cut off the current from the motor and check the rotation thereof. 115 120 125

What I claim and desire to secure by Letters Patent of the United States is:—

1. In a winding engine, a drum, a reversible electric motor for driving the drum in two directions, gearing connecting the mo- 130

tor and drum, and means controlled by the thrust on said gearing to cause the motor to rotate in either of two directions during normal operation.

5. 2. In a winding engine, a drum, a reversible electric motor for driving the drum in two directions, gearing connecting the motor and drum, a controller for the motor, and means for operating said controller in accordance with variations in thrust on said gearing to cause the motor to rotate in either of two directions during normal operation.

3. In a winding engine, a drum, a reversible electric motor for driving the drum in two directions, worm gearing connecting the motor and drum, and means whereby variations in thrust either side of normal exerted on said worm gearing causes the motor to rotate in one direction or the other to wind in or pay out the line.

4. In a winding engine, a drum, a motor for driving the drum in two directions, a power transmitting shaft mounted for endwise movement, a worm on said shaft, a worm gear meshing with said worm and transmitting power therefrom to the drum, and means whereby endwise movement of said shaft caused by variations in thrust exerted by the drum on said worm causes said motor to rotate in one direction or the other during normal operation.

5. In a winding engine, a drum, a motor for driving the drum in two directions, a power transmitting shaft mounted for endwise movement, a cushioning means resisting endwise movement of said shaft, a worm on said shaft, a worm gear meshing with said worm and transmitting power therefrom to the drum, and means whereby variations in thrust either side of normal exerted on said worm gearing causes endwise movement of said shaft and causes the motor to rotate in one direction or the other to wind in or pay out the cable.

45. 6. In an engine, a winding drum for a line, an electric motor for operating said drum, a controller for the motor, means responsive to temporary variations in tension on the line for operating said controller to rotate said motor in a direction tending to correct the variation in tension, and means responsive to the paying out or winding in of said line for checking the rotation of said motor.

7. In an engine, a winding drum for a line, associated means comprising an electric motor for putting the line under tension, means responsive to temporary variations in tension on the line for causing said motor to rotate in a direction tending to correct the variation in tension, and means responsive to the paying out or winding in of the line for checking the rotation of said motor.

8. In an engine, a winding drum for a line, associated means comprising an electric motor for putting the line under tension, means

responsive to normal tension on the line for deenergizing said motor, and means responsive to an increase or decrease in tension on the line for energizing said motor and causing it to rotate in one direction or the other to pay out or wind in the line.

9. In an engine, a winding drum for a line, associated means comprising a reversible electric motor for putting said line under tension, means responsive to normal tension on the line for deenergizing said motor, means responsive to variations in tension on the line for rotating said motor in a direction tending to correct the variation of tension, and means responsive to the paying out and winding in of the line for checking the rotation of said motor.

10. In an engine, a winding drum for a line, an electric motor for operating said drum in either of two directions, a member for controlling said motor, automatic means responsive to variations in tension on the line for actuating said member, means for operating said member manually, and means under control of the operator for disabling said automatic means during manual operation.

11. In an engine, a winding drum for a line, an electric motor for operating said drum, means whereby the motor is energized on a variation in tension in the line tending to rotate the motor in a direction to pay out or wind in the line to correct such variation, and automatic means operable while said line is being paid out or wound in to check the rotation of said motor and increase or decrease respectively the tension in the line.

12. In an engine, a winding drum, an electric motor for operating said drum, a controller constructed and arranged normally to break the circuit to said motor and operative on movement in opposite directions from the normal position for closing circuits to the motor to cause the same to rotate in one direction or the other depending upon the direction in which said controller is moved, means responsive to variations in tension on the line for moving said controller away from normal position and thereby cause said motor to operate said drum, and automatic means operable in response to the paying out or winding in of the line for checking the rotation of said motor.

13. In an engine, a winding drum, an electric motor for operating said drum, a controller constructed and arranged normally to break the circuit to said motor and operative on movement in opposite directions from the normal position for closing circuits to the motor to cause the same to rotate in one direction or the other depending upon the direction in which said controller is moved, means responsive to variations in tension on the line for moving said controller away from normal position and thereby cause said motor

to operate said drum, and a brake for normally preventing rotation of said motor when said controller is in neutral position and operative on movement of said controller in either direction from normal for releasing said brake.

14. In an engine, a winding drum, an electric motor for operating said drum, a controller constructed and arranged normally to break the circuit to said motor and operative on movement in opposite directions from the normal position for closing circuits to the motor to cause the same to rotate in one direction or the other depending upon the direction in which said controller is moved, means responsive to variations in tension on the line for moving said controller away from normal position and thereby cause said motor to operate said drum, and an electric brake for normally preventing rotation of said motor and operative on movement of said controller to neutral position.

15. Apparatus for controlling the cable of a towing or mooring machine or the like, comprising a drum for winding up the cable, an electric motor, a yieldable driving connection between said motor and said drum whereby said drum is movable independently of said motor in response to the tension of the cable, means operated responsively to said independent movement of the drum for controlling the energization of said motor to cause said motor to pay out cable upon the occurrence of a predetermined maximum tension and to wind up cable upon the occurrence of a predetermined minimum tension whereby a predetermined mean tension is maintained.

16. In a winch, the combination of a windlass, a cable secured at one end thereto and adapted to be secured at its opposite end to an object relatively foreign to said windlass, a motor adapted to operate said windlass to wind up said cable when it is slack and to reverse said windlass to pay out said cable when it is under severe tension, yielding means adapted to be put under tension by said cable acting through said windlass, means governed by said yielding means for automatically energizing said motor to reverse the same to pay out said cable when the cable is under severe strain, and means for automatically energizing said motor to operate the same to wind up said cable when the cable is slack.

17. In a winch, the combination of a reciprocable member, a windlass, an electric motor, means for transmitting power from said motor to said windlass, an electric circuit for operating said motor, said operating circuit embodying a normally open contact, an electric circuit for reversing said motor, said reversing circuit embodying a normally open contact, a circuit closer for said reversing circuit adapted to be moved

into circuit-closing position by said reciprocable member, when said member has advanced to a predetermined point from central or idle position, and a circuit closer for said operating circuit adapted to be moved into circuit-closing position by said member when said member has retreated to a predetermined point from the advanced end of its path of travel.

18. In a winch, the combination of a reciprocable member, means for reciprocating said member, a cable drum and drum gear, a cable on said drum, means responsive to variations in tension on said cable and mounted on said reciprocable member for automatically operating and reversing said gear, and means adapted to be governed by the reciprocation of said member for controlling said operating and reversing means.

19. Apparatus for controlling the cable of a towing or mooring machine or the like, comprising a drum for winding up the cable, an electric motor, a driving connection between said motor and said drum including a member having cooperating parts relatively movable in response to the tension of the cable, a control member for said motor, and means for giving said control member movement of translation in response to relative movement of said parts to control the energization of said motor to pay out cable upon the occurrence of a predetermined maximum tension and to wind up cable upon the occurrence of a predetermined minimum tension, whereby a predetermined mean tension is maintained.

20. Apparatus for controlling the cable of a towing or mooring machine or the like, comprising a drum for winding up the cable, an electric motor, a yieldable driving connection between said motor and said drum, whereby said drum is movable independently of said motor in response to the tension of the cable, said connection including a shaft, means operated responsively to said independent movement of the drum in a direction parallel to said shaft for controlling the energization of said motor to cause said motor to pay out cable upon the occurrence of a predetermined maximum tension, and wind up the cable upon the occurrence of a predetermined minimum tension, whereby a predetermined mean tension is maintained.

21. Apparatus for controlling the tension of a cable of a towing or mooring machine or the like, comprising a drum for winding up the cable, an electric motor, a yieldable driving connection between said motor and said drum whereby said drum is movable independently of said motor in response to the tension of the cable, a controlling member operated responsively to said independent movement of the drum, said controlling member acting to effect the energization of

said motor to cause said motor to pay out cable upon the occurrence of a predetermined maximum tension, to de-energize the motor upon a predetermined mean tension in the cable and to energize the motor to wind up cable upon the occurrence of a predetermined minimum tension in the cable, whereby a predetermined mean tension is maintained.

10 22. In a winding engine, a winding drum and the line wound thereon, an electric motor for operating the same, means responsive to variations in tension on said line for automatically controlling the current to the 15 motor for driving the same in either of two directions for maintaining a substantially constant pull on the line, and means for changing the pulling capacity of the machine.

20 23. In a winding engine, a winding drum and the line wound thereon, an electric motor for operating the same, means responsive to variations in tension on said line for automatically controlling the current to the 25 motor for driving the same in either of two directions for maintaining a substantially constant pull on the line, and manually adjustable means for changing the pulling capacity of the machine.

20 24. In combination, a motor, a rotary member driven by said motor, a winding drum, a yielding power-transmitting connection between the rotary member and the drum, and means to maintain a substantially constant resistance to the turning of the drum by a hawser wound on the drum while the tension on the hawser is at substantially a predetermined amount, said means being operable by relative rotation of said rotary member and said drum to decrease the resistance to the turning of the drum by the hawser when the tension on the hawser is suddenly increased, and to increase such resistance when the tension on the hawser is increased above the predetermined amount for a relatively long period.

THOMAS SPENCER MILLER.
